UNITED STATES PATENT OFFICE

138,190

DESIGN FOR A TOY GUN

Rolf G. Swanson, Minneapolis, Minn.

Application March 16, 1944, Serial No. 112,932

Term of patent 3½ years

(Cl. D34—15)

To all whom it may concern:

Be it known that I, Rolf G. Swanson, a citizen of the United States, residing at Minneapolis, in the county of Hennepin and State of Minnesota, have invented a new, original, and ornamental Design for a Toy Gun, of which the following is a specification, reference being had to the accompanying drawing, forming a part thereof.

Fig. 1 is a side elevational view of the toy gun, showing my new design.

Fig. 2 is a top plan view thereof; and

Fig. 3 is a front elevational view thereof.

I claim:

The ornamental design for a toy gun, as shown.

ROLF G. SWANSON.
